UNITED STATES PATENT OFFICE.

HANS E. GRABAU, OF NEW YORK, N. Y.

HAMMER FOR BEATING LEAF METAL.

No. 814,003.

Specification of Letters Patent.

Patented Feb. 27, 1906.

Application filed May 1, 1905. Serial No. 258,246.

To all whom it may concern:

Be it known that I, HANS E. GRABAU, a citizen of the United States, residing at New York city, Brooklyn, county of Kings, and State of New York, have invented new and useful Improvements in Hammers for Beating Leaf Metal, of which the following is a specification.

This invention relates to a hammer more particularly adapted for beating leaf metal, though it may also be used for different purposes.

The invention consists, essentially, in interposing a yielding buffer or cushion of the construction hereinafter described between the hammer-actuating cross-head and the means for suspending the hammer from said cross-head. These buffers serve to take up the impact from the stroke and are not apt to be quickly destroyed by the severe pounding to which they are subjected.

In the accompanying drawings, Figure 1 is a front elevation of my improved hammer; Fig. 2, a side view thereof; Fig. 3, a horizontal section on line 3 3, Fig. 1; Fig. 4, a detail of the hammer-supporting rollers and lower buffers; Fig. 5, a detail showing the connection between cross-head and levers, and Fig. 6 a detail of the upper buffers.

The frame of the machine is composed of two parallel side plates *a*, connected by horizontal beams *a'*, to which they are bolted at *a''*. Within bearings *a''* turns the power-shaft *b*, carrying loose and fast pulleys *b'* *b''* and crank-disk *b''*. The belt-shifter *c* may be operated by a treadle *c'*.

Along upright rails *a'* of plates *a* moves a slide *d*, which is reciprocated by a disk *b''*. The connection between the parts *d* and *b''* is effected by a sectional link, the upper member *b''* of which is pivoted to disk *b''* by wrist-pin *b''*, while its lower member *d'* is pivoted to slide *d* at *d''*. The parts *b''* *d'* are connected by a clamp-screw *d''*, passing through a slot *d''* of member *d'*, so that the length of the link may readily be changed. From slide *d* projects forwardly a perforated block *d''*, through which passes a horizontal bar *e*, clamped thereto by screw *e'*. Upon each end of bar *e* is mounted an angular abutment or bracket *f*, which is perforated for the reception of the bar. The slide *d*, bar *e*, and brackets *f* collectively form the cross-head that actuates the hammer-head. The upper member of

bracket *f* is forked to grasp a lever *g*, hinged thereto at *g'*. The lower bifurcated arms *g''* of levers *g* embrace rollers *h*, journaled in bearings *h'*, which are supported by levers *g*. Around the rollers *h* passes an endless belt *i*, from which the hammer-head *j* is suspended, the latter being perforated for the passage of the belt. To guide the hammer, it is provided with grooved flanges *j'*, that engage rails *a'*.

Through the levers *g* pass screws *k*, the inner ends of which bear against sockets *l'* of holders *l*. These holders support rubber blocks or resilient buffers *m*, which are interposed between the holders, and consequently between the levers *g* and the lower arms of brackets *f*. The buffers will take up the strain during the operation of the hammer and will not be liable to be quickly destroyed by the severe shocks to which they are subjected.

To assist the buffers *m*, the bearings *h'* may be made slideable in boxes *g''* of arms *g''*, while lower buffers *n* are interposed between the bearings and the boxes. To further relieve buffers *m*, rods *o*, extending inwardly from upper arms of levers *g*, straddle boxes *p'*, formed on the outer ends of rods *p*, which are pivoted to slide *d* at *p''*. To the forked ends of rods *o* are bolted bearings *p''*, slideable in boxes *p'*. Upper resilient buffers *q* are interposed between the bearings *p''* and the boxes *p'*.

It is evident that either the first, second, or third set of buffers or any two of such sets may be omitted without departing from the spirit of my invention. By lengthening or shortening the adjustable link *b''* *d'* the approach of the hammer *j* toward the work-table *r* may be adjusted.

What I claim is—

1. A hammer for beating leaf metal provided with a cross-head having angular abutments, levers pivoted thereto, means for suspending a hammer-head from the levers, set-screws engaging the levers, holders engaged by the set-screws, and buffers supported by the holders and adapted to engage the abutments, substantially as specified.

2. A hammer for beating leaf metal provided with a slideable cross-head, levers pivoted thereto, bearings slideably supported by the levers, rollers journaled in the bearings, a belt surrounding the rollers, a hammer-head

suspended from the belt, and resilient buffers between the bearings and the levers, substantially as specified.

3. A hammer for beating leaf metal provided with a guideway and slideable cross-head guided thereby, levers pivoted thereto and having upwardly-extending arms, a belt connected to the lower free ends of the levers, a hammer-head suspended from the belt, and

resilient buffers between the cross-head and the upwardly-extending lever-arms, substantially as specified.

Signed by me at New York city, (Manhattan,) New York, this 29th day of April, 1905.

HANS E. GRABAU.
